CLAIM

The ornamental design for a brace support hook tab, as shown and described.

DESCRIPTION

FIG. 1 is a perspective view of a first embodiment showing the new design for a brace support hook tab;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof;

FIG. 8 is a perspective view of a second embodiment showing the new design for a brace support hook tab;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

The portions of the back brace support hook tab in FIGS. 1-14 shown in even length broken lines are portions of the back brace support hook tab that form no part of the claimed design. The dot-dash broken lines show the bounds of the claimed design and form no part of thereof. The smaller even length broken lines on the claimed surface represent stitching, and also form no part of the claimed design.
